FOLDABLE HEADREST

Siegfried Marx, New York, N. Y.

Application March 2, 1938, Serial No. 193,382

2 Claims. (Cl. 5—337)

My invention relates to a foldable support and more particularly to a foldable headrest.

On excursions or trips people very often desire to relax for a while in a lying position. Most people prefer to rest with their head in a somewhat raised position, but it is inconvenient to take along bulky pillows, which require ample space in a bag.

One object of my invention is to provide a foldable headrest, which is entirely flat in collapsed position, so that it may be easily taken along in a bag or even in a clothing pocket.

Another object of my invention is to provide a foldable headrest consisting of a minimum of elements, which may be easily manufactured at comparatively low costs.

In order to carry out my invention into practice, I provide a foldable headrest comprising two polygonal frames, means pivotally connecting said frames with each other at an intermediate point thereof, said frames being adapted to be entirely internested in each other in a straight plane, and a strip of flexible material, said strip connecting the upper ends of said frames with each other. If the headrest is to be used at the beach, preferably a second strip of flexible material is provided, which connects the lower ends of said frames and prevents an undesired sinking into the sand. In a preferred embodiment of the headrest, the frames are of substantially 8-shape, so that only a single pivotal connection at the restricted portion of said 8-form becomes necessary. Each of the frames may have flattened upper and lower ends and may be formed of a flat metal band.

The above mentioned objects and advantages as well as other objects and advantages will be more fully disclosed in the following specification reference being had to the accompanying drawing forming part of this specification, in which:

Fig. 1 is a front elevational view of the foldable headrest in collapsed position,

Fig. 2 is a side elevational view of the foldable headrest in collapsed position, and

Fig. 3 is a perspective view of the foldable headrest in opened position.

Referring now to the drawing, 10 indicates an outer frame and 11 indicates an inner frame of the headrest. Both frames are of substantially 8-shape with flattened upper ends 12, 13 and flattened lower ends 14, 15 respectively. The frames are provided with registering holes 16 at their intermediate restricted portion, through which a pivotal means, such as a rivet 17, a screw

or the like, passes to provide a pivotal connection between said frames. The upper ends 12 and 13 of the frames 10 and 11 are connected with each other by a flexible strip 18 of fabric or any other suitable material, the ends of which being attached to said ends of the frames by clamping means or in any other suitable manner. For example, the end of the fabric may surround the end of the frame in form of a loop and may be secured to the main portion of the fabric by 10 means of a seam. Likewise, the lower ends 14 and 15 of the frames 10 and 11 are connected with each other by a second strip 19. This second strip 19 could be omitted, if desired, but I prefer to arrange the strip, as it serves to 15 strengthen the construction, if the headrest is in open position as shown in Fig. 3, and to prevent an undesired sinking into loose sand, if the headrest is used on the beach.

In the embodiment shown in the drawing, each 20 of the frames is formed of a flat metal band, the free ends of which loosely overlapping each other at the intermediate restricted portion of the frames and being clamped together by the pivotal connecting means 17. If desired, however, the free ends of the metal band could be welded to each other.

As clearly shown in Fig. 1, the inner frame 11 has a form similar to the outer frame 10, but its measurements are somewhat smaller than that 30 of the outer frame, so that said two frames 10 and 11 may be entirely internested in each other in collapsed position of the headrest. Therefore, the headrest is absolutely flat in collapsed position, as shown in Fig. 2, and has a thickness a 35 equal to the width of the metal band forming the frame, so that the headrest may be easily taken along in a bag or a clothing pocket. If the headrest is to be used, the frames 10 and 11 are moved relatively to each other about the pivot 17 and are brought into the position shown in Fig. 40 3, which is determined by the length d of the strips 18 and 19. Then the user may conveniently rest his head on the flexible upper strip 18.

In a preferred embodiment of my invention, 45 I make the length b of the headrest equal to about 8", the width c equal to about 4 $\frac{1}{4}$ ", the thickness a equal to about $\frac{1}{4}$ ", and the length d of the strips equal to about 6", but I do not wish to be limited to said measurements.

I have described a preferred embodiment of my invention, but it is clear that numerous changes and omissions may be made without departing from the spirit of my invention. For example, the frames could be of another polyg- 55

onal form than of 8-shape, or the upper end of the frames may not be flattened, or the lower part of the frames ~~may~~ not be closed. Furthermore, I could use the foldable support for any other purposes than for a headrest only.

What I claim is:

1. A foldable headrest or the like comprising two frames of substantially 8-shape, each of said frames having flattened upper and lower ends 10 and being formed of a flat metal band, the free ends of said metal band overlapping each other at one side of the intermediate restricted portion of the 8-form, all the adjacent parts and the overlapping parts of said frames being provided 15 with registering openings at the intermediate restricted portions, a common pivot pin passing through said openings and holding the overlapped parts together, said frames being adapted to be entirely internested in each other in a plane, 20 and a strip of flexible material, said strip con-

nected the upper ends of said frames with each other.

2. A foldable headrest or the like comprising two frames of substantially 8-shape, each of said frames having flattened upper and lower ends 5 and being formed of a flat metal band, the free ends of said metal band overlapping each other at one side of the intermediate restricted portion of the 8-form, all the adjacent parts and the overlapping parts of said frames being provided 10 with registering openings at the intermediate restricted portions, a common pivot pin passing through said openings and holding the overlapped parts together, said frames being adapted to be entirely internested in each other in a plane, and two strips of flexible material, one of said strips connecting the upper ends of said frames with each other, the other one connecting the lower ends of said frames with each other.

SIEGFRIED MARX. 20
